SPINNING DEVICE

Carl Theodor Pastor, Huels Uber Krefeld, Germany

Original application August 11, 1937, Serial No. 158,469. Divided and this application November 5, 1938, Serial No. 239,150. In Germany August 13, 1938

6 Claims. (CL. 57—77)

My invention relates to a spinning device and more particularly to a spinning cup mounted on a rapidly rotating driving shaft.

This application is a division of applicant's copending application filed Aug. 11, 1937, Ser. No. 158,469.

One object of my invention is to mount the spinning cup on the shaft in such a manner that it is held firmly on the shaft even at the highest speed of revolution, but may be removed readily if desired.

A further object of my invention is to provide a mounting for the spinning cup on the driving shaft which insures an automatic accurate centering of the two elements relative to one another.

According to my invention, I accomplish the above-mentioned and other objects, which will appear as the description proceeds, by the combination with a vertical driven shaft provided with a central bore and having its upper end of conical shape, of a spinning cup comprising a central hub having an axial bore and two oppositely disposed conical seats formed at the ends of said bore, respectively, the lower of said seats bearing on the upper end of said shaft, and a pin slidably disposed within the bore of the shaft and projecting upwardly through said axial bore in said hub, said pin having at its upper end a head tapered on a conical surface towards said pin to engage the upper conical seat in said hub.

My invention is illustratively exemplified in the accompanying drawing, the single figure of which shows one embodiment of my invention partly in elevation and partly in section.

In the drawing, 10 denotes the vertical hollow shaft of an electromotor 11 enclosed in a two part motor casing 12. The upper end of the hollow shaft 10 is provided with a reinforced rim 10a. A second hollow shaft portion 13 formed at its lower end with a seat and a corresponding reinforced rim 13a is supported on the upper end of shaft 10 and projects upwardly from the casing 12 through an opening 14 in the latter. The upper end of the hollow shaft portion 13 is of conical shape, and between this upper conical end and the part of the shaft 13 extending into the motor casing 12, there is provided on the shaft portion 13 a flange 15 overlapping and covering the opening 14 in the motor casing 12, whereby precipitating liquid is prevented from entering the hollow shaft or the motor.

The spinning cup 16 comprises an axially bored

central hub 17, having a conical seat 18 at the lower end of the bore and a second oppositely disposed conical seat 19 at the upper end of the bore. The can 16 is seated with the lower conical seat 18 on the conical upper end of the hollow shaft portion 13 and is held in this position by means of a pin 20 having a diameter slightly smaller than that of the bores in the hub 17, hollow shaft portion 13 and hollow shaft 10, and extending slidably through said hub 17 and shaft portion into said hollow shaft. The pin 20 comprises at its upper end a head 21 tapered on a conical surface towards the pin and engaging the upper conical seat 19 in the hub 17 thereby pressing the can 16 with the lower conical seat 18 in the hub 17 against the upper conical end of hollow shaft portion 13. At the same time the pin 20 effects automatically an accurate centering of the cup relatively to the driving shaft.

When the device starts to rotate, the pin 20 tends to rise within the hollow shaft 10 and hollow shaft portion 13, and, when the number of revolutions exceeds a critical period, the pin drops again into the shaft. This free oscillation of the pin 20 is facilitated by the portion thereof within the hollow shaft portion 13 and hollow shaft 10 being tapered at 22.

The hollow shaft 13 with the spinning cup 16 is likewise lifted off the shaft 10 at the critical number of revolutions before a positive coupling is effected.

Although only one preferred form of my invention has been illustrated and described in detail, it will be apparent to those skilled in the art that various modifications may be made therein without departing from the spirit of my invention as set forth in the appended claims.

I claim:

1. In a spinning device, the combination with a vertical driven shaft provided with a central bore and having its upper end of conical shape, of a spinning cup comprising a central hub having an axial bore and two oppositely disposed conical seats formed at the ends of said bore, respectively, the lower of said seats bearing on the upper end of said shaft, and a pin slidably disposed within the bore of the shaft and projecting upwardly through said axial bore in said hub, said pin having at its upper end a head tapered on a conical surface towards said pin to engage the upper conical seat in said hub.

2. A spinning device, as claimed in claim 1,

comprising further an electromotor, said driven shaft being formed by the shaft of said motor.

3. A spinning device, as claimed in claim 1, in which said driven shaft comprises two superimposed portions, and a driving connection is provided between said portions.

4. A spinning device, as claimed in claim 1, in which the portion of said pin disposed within the bore of said shaft is tapered.

10 5. A spinning device, as claimed in claim 1, comprising a flange element on said shaft below

said spinning cup and adapted to prevent flow of liquid to the lower portion of the shaft.

6. A spinning device, as claimed in claim 1, comprising further a motor, and a casing for said motor, said driven shaft projecting through 5 said casing, and a flange formed on said shaft below the spinning cup and outside the motor casing, said flange covering the opening in said casing through which the shaft projects.

10

CARL THEODOR PASTOR.
